UNITED STATES PATENT OFFICE.

STEPHEN J. JACOB, OF APPLETON, WISCONSIN.

PAPER PERFORATOR.

Application filed December 26, 1924. Serial No. 758,025.

To all whom it may concern:

Be it known that I, STEPHEN J. JACOB, a citizen of the United States, residing at Appleton, county of Outagamie, and State of Wisconsin, have invented new and useful Improvements in Paper Perforators, of which the following is a specification.

This invention relates to improvements in combined grippers and perforators for printing presses.

It is an object of this invention to provide for printing presses a paper gripper having a paper perforating blade resiliently mounted thereon and operable adjacent one side of the gripper so that the paper may be perforated in close proximity to the printing thereon.

Another object of this invention is to provide a paper gripper having mounted thereon a paper perforator which, by a reversal of the relative mounting between the gripper and perforating blade, may be alternatively used for right or left hand perforating.

A further object of this invention is to provide a simplified assembly of the gripper and perforating blade reversible in character and yet sturdy in structure.

In the drawings:

Fig. 1 is a fragmentary diagrammatic side elevation of a printing press showing the gripper and perforator mounted thereon.

Fig. 2 is a side elevation of one form of combined gripper and perforator.

Fig. 3 is a plan view of the same.

Fig. 4 is a fragmentary isometric view of the same with a section taken on the line 4-4 of Fig. 3.

Fig. 5 is a plan view of a preferred form of the device.

Fig. 6 is a fragmentary sectional view taken on the line 6-6 of Fig. 5.

Like parts are identified by the same reference characters throughout the several views.

The printing press includes a stationary type carrying bed 1 and a platen 2 hinged at 3 for movement to and from the bed 1. The platen has also a horizontal movement toward the bed 1. This movement coupled with the pivotal movement brings the paper shown at 4 into contact with the type (not shown) secured in the chase 5 carried by the bed. The mechanism for operating the

platen has not been shown for the reason that it is old and does not constitute a part 55 of this invention.

Carried by the platen for relative pivotal movement thereto is a gripper plate 6 which, in the forms shown in Figs. 2 and 3 comprises a flat piece of metal having a pair of apertures 7, each situated adjacent an end of the plate and adapted to receive a bolt 8 on the printing press. There are two bolts 8 provided upon the press, one at the right and the other at the left thereof, only one 65 bolt being shown, however. The gripper plate is secured to the printing press by means of a nut 9 upon bolt 8. The gripper plate has a recessed or cutaway portion 10 and at each end of the recess a slot 11 providing a pair of opposite tongues 12 adjacent each slot 11. Positioned upon the plate is a perforating blade 13 reciprocable vertically thereof and having each end extending into a corresponding slot 11. This blade 13 75 is suspended at each end by springs 14, each secured to the plate 6 (Figs. 2 and 3) by screws 20. The springs 14 are each slotted at 15 to receive a portion of the blade, and the blade is slotted at each end at 16 to 80 receive a portion of an associated spring. The springs and blade are thus interlocked to maintain the blade 13 in its position relative to the plate. Each of the slots 16 are flared outwardly at 17 to provide working 85 space for the spring 14 as the blade 13 reciprocates. For assisting the springs and slots 11 in maintaining the blade at substantially right angles to the gripper plate 6, a block 18 is provided, secured to the 90 plate by a pair of screws 19. A shim 21 is positioned between each of the springs and the plate 6, the screws 20 forcing the overlapping portions of the springs about their respective shims for giving additional binding effect between the screws and gripper plate.

The modified form of gripper and perforator shown in Figs. 5 and 6, is similar to that shown in Figs. 2 and 3, but differs in 100 that one end only is provided with an aperture 7' adapted to receive a bolt 8 on the printing press. At each end of the tongue portion 22 is provided a slot similar to the slots 11 in the form of gripper shown in 105 Figs. 2 and 3, the perforator 13 being recip-

2
rocable in such slots in a manner similar to that disclosed in Figs. 2 and 3. Mounted upon the tongue intermediate its end is a block 18 for assisting the slots 11 and springs 14 in guiding the perforating blade vertically relative to the plate and secured to the tongue by a pair of screws 19.

The modified form of gripper plate 6 is provided with recesses 23 at each end and 10 each side thereof. These recesses are adapted to receive one end of the springs 14' which are secured to the gripper plate by screws 24, and the sides of the recesses serve to prevent the springs from turning about 15 their respective screws. In the form of gripper plates shown, each of the screws 19 and 24 are inserted into apertures which pass completely through the gripper plates so that the screws may be engaged therewith 20 at either side of such plate. Thus the arrangement shown in Figs. 5 and 6 may be used for making right hand perforations and by a reversal of the parts be used for making left hand perforations. If it is desired 25 to make left hand perforations, all that is necessary is to remove the screws 19 and 25 for releasing the springs 14' and block 18, reversing the gripper plate so that the recessed side of the tongue 22 is upon the 30 lower side of the gripper plate from that shown in Fig. 5. The springs 14' are then placed in their corresponding recesses 23 upon the opposite side of the gripper plate, the block 18 is placed upon the corresponding 35 side of the gripper plate, and the screws are then inserted in their respective apertures for securing the springs and block to the plate. In the form of perforator and gripper shown in Figs. 2 and 3, the plate 6 is secured to the press by securing the left 40 hand end thereof to the right of the press for right hand perforating. When it is desired to make left hand perforations the right hand end of the plate as shown in a 45 Figs. 2 and 3, is secured to the press in a manner similar to that previously described.

In operation, the perforating device and gripper are brought into contact with the 50 paper when, by reason of the horizontal and pivotal movement of the platen, the perforating blade is brought into contact with a portion of the bed 1 thus forcing the perforating blade against the supporting springs and relatively toward the gripper plate. 55 The pressure exerted by the perforating blade upon its supporting springs causes the gripper plate to come into contact with the paper upon the platen and to hold it in stationary position during the printing and 60 perforating process. When the platen recedes from the bed of the printing press, the gripper plate follows the platen in its movement and maintains contact with the paper until the supporting springs of the 65 perforating blade force the blade away from

the paper. The platen then is subsequently withdrawn from the gripper plate to permit replacement of the printed and perforated sheet.

I claim:

1. In a perforating device having a reciprocatory perforating blade, a gripper plate provided with means for resiliently supporting said blade and having one side cut away to provide a recess within which said blade may reciprocate, whereby printing may be done in close proximity to said blade. 70
2. In a perforating device having a resiliently supported reciprocatory perforating blade, a gripper plate having one side cut away to provide a recess within which said blade may reciprocate and provided with ends each having a depression adapted to receive a spring for resiliently supporting said blade, whereby to maintain said blade in alignment with said recess. 80
3. In a perforating device having a resiliently supported, reciprocatory perforating blade, a gripper plate having one side cut away to provide a recess within which said blade may reciprocate and provided with ends each having its opposite faces provided with a depression adapted to receive a spring for resiliently supporting said blade, whereby said blade may alternatively be mounted upon each side of said plate, thereby to provide a reversible right or left hand perforator. 85
4. In a device of the character described, the combination with a gripper plate having a recessed side and provided with slots at each end thereof communicating with the recess, of a perforating blade reciprocable in said recess and slots, and supporting springs each secured to said plate and engaged with said blade, said springs and blade being slotted for inter-engagement. 100
5. In a device of the character described, the combination with a gripper plate having a recessed side and depressed ends, of a perforating blade reciprocable in said recess, and supporting springs each having one end disposed in a depression and secured to said plate, said springs and blade being slotted for inter-engagement. 110
6. In a device of the character described, the combination with a gripper plate having a recessed side provided with slots at each end thereof and depressed ends, of a perforating blade reciprocable in said recess and slots, and supporting springs each having one end disposed in a depression and secured to said plate, said springs and blade being slotted for inter-engagement. 120
7. In a device of the character described, the combination with a gripper plate having a recessed side, of a perforating blade reciprocable in said recess, supporting springs each secured to said plate and engaged with 130

said blade, and a guide block secured to said plate intermediate the ends of said blade and adjacent said recess.

8. In a device of the character described, the combination with a gripper plate having a recessed side, of a perforating blade reciprocable in said recess, supporting springs each secured to said plate, and a guide block secured to said plate intermediate the ends of said blade and adjacent said recess, said springs and blade being slotted for inter-engagement.

9. In a device of the character described, the combination with a gripper plate having a recessed side and depressed ends, of a perforating blade reciprocable in said recess, supporting springs each having an end secured in the depression, and a guide block secured to said plate intermediate the ends of said blade and adjacent said recess, said springs and blade being slotted for inter-engagement.

10. In a device of the character described, the combination with a gripper plate having a recessed side provided with slots and depressed ends, of a perforating blade reciprocable in said recess and slots, supporting springs each having an end secured in a depression, and a guide block secured to

said plate intermediate the ends of the blade and adjacent the recess, said springs and blade being slotted for inter-engagement.

11. In a device of the character described, the combination with a gripper plate, of a perforating blade, and supporting springs provided with means for alternatively securing them upon opposite sides of the plate, whereby to provide a reversible perforator for making right or left hand perforations.

12. In a perforating device having a resiliently supported, reciprocatory perforating blade, a gripper plate having one side cut away to provide a recess within which said blade may reciprocate, said plate being provided with slots each disposed at one end of said recess to constitute the continuation thereof.

13. In a device of the character described, the combination with a gripper plate comprising a pair of ends each having oppositely depressed faces and a recessed intermediate portion connecting said ends, of a perforating blade reciprocable in said recess, supporting springs engaged with said blade and each having one end engageable alternatively in either of said depressed faces for securing said springs to said gripper.

STEPHEN J. JACOB.
